G. F. Chapman

United States Patent Office.

C. F. ANTHONY, OF CHICAGO, ILLINOIS, ASSIGNOR TO HIMSELF AND JOHN CHARTERS.

Letters Patent No. 78,350, dated May 26, 1868.

IMPROVED HASSOCK-MACHINE.

The Schedule referred to in these Letters Patent and making part of the same.

TO ALL WHOM IT MAY CONCERN:

Be it known that I, C. F. ANTHONY, of Chicago, in the county of Cook, in the State of Illinois, have invented an Improved Hassock-Machine; and I do hereby declare that the following is a full and exact description thereof, reference being had to the accompanying drawings, and to the letters of reference marked thereon, making a part of this specification, in which—

Figure 1 is a central sectional elevation of my invention.

Figure 2 a top view of the same.

Figure 3, drawing 2, a perspective representation of that part of the hoop in which the hassock is formed.

Figure 4 a top view of the bottom of the hoop.

The nature of this invention consists in the use of a three-part hoop, divided horizontally a little above the middle, and the lower part divided vertically and hinged at the bottom, the top part being used for holding the material necessary for stuffing a hassock, and the bottom part for giving the hassock the required shape.

The three parts are made to form a fluted cylinder, of such shape as the hassock is to have when completed, and the rim of the lower parts has a series of brads projecting upward and into the rim of the upper part, for the purpose of holding the covering of the hassock in place, when being filled.

To enable others skilled in the art to make and use my invention, I have marked corresponding parts with similar letters, and will now proceed to give a detailed description.

B B, fig. 1, and fig. 3, drawing 2, represent the lower part of the hoop, which is made of two pieces of thin sheet metal, and with convex flutes on its periphery, corresponding with the shape which the hassock is to have when finished, and its lower edge is rigidly fastened to a two-part bottom, P P, figs. 3 and 4, drawing 2, hinged together at H H, for the purpose of permitting the parts B B to be opened, as at fig. 3, and the hassock removed. The bottom, P P, has depressions e e, &c., made in it, of such form as is desirable for the top of the hassock to have, and the top of the hoop B B is rigidly attached to a two-part rim, C C, which has a series of sharp brads, a a, &c., projecting upward, and used for holding the hassock-covering in place when being stuffed.

Hooks or catches F F are pivoted to the edges of the rim C, and fasten over pins b in the opposite rims, and are used to hold the parts B closely together.

The upper part, A, of the hoop is made of the same material as the parts B B, and is also fluted to correspond with them, but is made of a single sheet of metal, and it has a wooden rim, D, attached to its lower edge, as seen at fig. 1, corresponding with the rim C C of the parts B B. This rim has holes in its under side, in which the brads a a, &c., fit, when the two rims are put together, and has metal guides, I I, fig. 2, put through it, and projecting downward and into holes S S in the rim C C, by which means the top hoop is held directly over the parts B B.

E represents a wooden follower, whose periphery is made to conform to the shape of the hoop, and is used, in conjunction with a screw, L, and press-frame K K, for compressing the stuffing in the hassock.

Operation.

The covering of the hassock should be made to conform to the shape of the hoop B B, (when closed,) in which it is put top downward, and the bottom edge hooked over the brads a a, &c., after which the top, A, should be put on the part B B, as seen at fig. 1, and the whole set in the press-frame K, having previously filled the hoop with stuffing. The compressing is done by simply turning the screw L, in the usual manner for this kind of work. To remove the hassock, the top, A, should be taken off, and the edges of the covering taken from the brads a a, after which the catches F can be loosened, and the parts B B opened, as seen at fig. 3, drawing 2.

This arrangement is quite simple, yet of importance for the purpose designed, as much difficulty is experienced in removing a hassock from a single hoop, and also holding the edge of the covering when being filled. Hence the usefulness of the invention is very evident.

Having thus described my invention, what I claim, and desire to secure by Letters Patent of the United States, is—

The three-part hoop A B B, whose top, A, is removable, and the lower part B B hinged at the bottom, and having a rim, C C, with projecting brads α α , &c., for holding a hassock-cover, substantially as and for the purpose set forth.

C. F. ANTHONY.
